(57) **CLAIM**

The ornamental design for a vehicle wheel, as shown and described.

DESCRIPTION

FIG. 1 is a front elevational view of a vehicle wheel showing our new design; and,

FIG. 2 is a perspective view thereof.

The ghosted or low contrasted areas in the drawings illustrated portions of the vehicle wheel that form no part of the claimed design.

1 Claim, 2 Drawing Sheets Fig. 1

Fig. 2
